UNITED STATES PATENT OFFICE.

ARTHUR MOORE, OF WAR EAGLE, WEST VIRGINIA.

AUTOMATIC REVOLVING CAR-DUMP.

SPECIFICATION forming part of Letters Patent No. 790,586, dated May 23, 1905.

Application filed May 14, 1904. Serial No. 207,960.

To all whom it may concern:

Be it known that I, ARTHUR MOORE, a citizen of the United States, residing at War Eagle, in the county of Mingo and State of West Virginia, have invented a certain new and useful Improvement in Automatic Revolving Car-Dumps, of which the following is a specification.

My invention relates to apparatus for unloading cars, and has for its object to provide means for dumping an entire car-load of coal, ore, or any similar material by turning the car completely over and allowing the contents to fall out.

Cars and like appliances of the construction in common use are usually emptied by opening a trap in the bottom of the car and allowing the contents to fall through. In practice there are serious objections encountered in the use of such cars, among which are the complicated character thereof, the height of the bottom of the car above the track necessary to accommodate the trap, the liability of accidental opening of the trap, thus spilling the contents along the track, the additional initial cost, and the necessary expense of repairs.

In my improved dumping device a coal, ore, or like car of any construction may be dumped, the dumping being accomplished by simply turning the car completely over and allowing the contents to fall out.

With these and other objects in view my present invention consists in the combination and arrangement of parts, as will be hereinafter more fully described, shown in the accompanying drawings, and particularly pointed out in the appended claims, it being understood that changes in the form, proportion, size, and minor details may be made within the scope of the claims without departing from the spirit or sacrificing any of the advantages of my invention.

In the accompanying drawings, Figure 1 represents an end view of my improved car-dump in position to receive a car for dumping, the positions of the cars upon the dump being shown in the dotted lines. Fig. 2 is a side elevation. Fig. 3 is a vertical section taken on line 3 3 of Fig. 1, and Fig. 4 is a de-

tail view of the four-way valve used to admit fluid to the various cylinders employed for operating means for holding the cars against displacement during rotation.

Like reference-numerals designate corresponding parts throughout the various views.

In the preferred embodiment of my construction I mount a shaft 1 of sufficient strength in suitable journal-bearings 2. Upon such shaft 1 I mount a plurality of **I**-beams 3 3 by passing shaft 1 therethrough. I arrange the **I**-beams in a parallel series, as shown, and secure them against rotary displacement by a key or in any other approved manner.

About shaft 1 as an axis I construct a plurality of circular members 4 4, with **I**-beams 3 3 as diameters. At a point approximately midway between the middle of such **I**-beams and their ends I erect uprights 5 5, which occupy the positions as sectors of the circular members and at right angles to said **I**-beam 3 3. These uprights 5 5 serve to strengthen the structure and to serve as guides for the clamping device to be hereinafter described. To further strengthen the structure, I employ braces 6 6, as shown.

Upon **I**-beams 3 3 as a platform I secure rails 7, 8, 9, and 10 parallel with shaft 1, rails 7 and 8 being upon one face of the platform and rails 9 and 10 upon the opposite face. Rails 7 and 9 are located nearer to shaft 1 than rails 8 and 10, so that the center of gravity of a car standing upon either of such pair of rails is not directly over shaft 1, but some- what to one side thereof.

To prevent displacement of the cars while being dumped, I provide a plurality of clamping members 11 11, consisting, preferably, of **I**-beams disposed transversely above each car and adapted to assume the positions indicated at 11' 11' and to forcibly hold each car against displacement. As a means for actuating such clamping member I preferably provide a plurality of vertically-disposed cylinders 12 12 with pistons therein, as indicated. Rods 13 13, connected with such pistons, are pivotally connected with the ends of clamping members 11 11. To operate the clamps, the cylinder receives between the end near-

est the clamping member and the piston any desired fluid under pressure, as air, steam, or water conducted to and into such cylinders through pipes 14 14.

5 For the purpose of preventing sidewise displacement of the car I provide a plurality of clamping members 15 15, preferably constructed of heavy wooden timbers, disposed longitudinally with and adapted to clamp the 10 sides of a car, as indicated at 15' 15'. As a means for actuating such clamping members I provide a second series of cylinders 16 16, horizontally disposed with pistons therein and thrust-rods connecting such pistons with 15 the clamping members 15 15. These cylinders are adapted to receive a fluid under pressure at the end opposite such clamping member from pipes 14 14. The introduction of fluid under pressure from pipes 14 14 to cylinders 12 12 and 16 16, as indicated, forces 20 clamping members 11 11 and 15 15 toward and upon the car, thus retaining the car securely in position while being turned entirely over. When the rotation of the dump has 25 been completed and it is desired to remove the car, fluid under pressure is admitted to the opposite ends of cylinders 12 12 and 16 16 through pipes 17 17 and the first-admitted fluid allowed to exhaust. This produces an 30 opposite movement of the pistons and causes clamping members 11 11 and 15 15 to release the car from pressure and to assume the positions shown in the drawings. To control the flow of the pressure-exerting fluid, I prefer 35 to introduce four-way valves 18 and 19 into the system of pipes. These valves are shown in detail at Fig. 4 and are preferably so constructed and disposed that with the valve-lever 20 in the position shown in Fig. 40 the fluid admitted at 21 passes through such valve into pipes 14, causing a clamping pressure to be exerted upon members 11 11 and 15 15, and the fluid contained in the cylinders passes out through the other passage 45 of the valve and exhausts at 22. By rotating valve-lever through one-quarter of a revolution to position 20^a fluid admitted at 21 passes through the valve and into pipes 17 17, and the fluid in the cylinders and pipes 14 14 50 exhausts through the valve and exhausts through port 22, moving the clamping members from clamping positions. When desired to lock 55 the pressure-exerting fluid within the cylinders and pipes, the valve-lever is rotated to position 20^b, which completely closes all ports. These valves I prefer to mount upon shaft 1, as indicated, and to admit the fluid to them by means of an opening 23, formed longitudinally within and concentric with the axis of 60 such shaft. Within this opening may be inserted pipe 24, connected with such valves and connected at its other end by a swivel-joint 25 with a supply-pipe 26 from any convenient source. To more conveniently op-

erate such valves, I pivotally secure to any 65 convenient portion of the structures levers 27 27, one end thereof connected by a rod 28^a with valve-levers 20 in any desired manner.

It will be understood that the unbalanced weight of a car upon the upper face of the rotating platform, as explained, will cause the platform and the structure secured thereto to rotate in the direction indicated by the arrow without the application of external motive power. As an auxiliary means for rotating such structure when desired or for the purpose of accurately adjusting it at any desired position I form about the periphery of one or more of circular members 4 a series of gear-cogs 28 and provide one or more 70 cogged pinions 29, journaled externally of and eccentrically to the circular member and adapted to engage cogs 28. Any convenient power may be utilized to operate the pinion 29 and may be connected therewith in 75 any desired manner. To control the velocity of rotation and to stop and lock the rotating structure at any desired point, I provide a brake adapted to engage therewith, and preferably in the form of a band or bands 80 30, extending entirely around one or more of the circular members, with the ends severally pivotally secured to the cross-head 31 of a lever 32, fulcrumed at 33 to any convenient stationary member. The lever 32 may be 85 operated by hand; but I prefer to connect the end 34 thereof by rod 35 with a piston working in a cylinder 36, adapted to throw lever 32 to the position 32' or any intermediate point, thereby tightening brake-band 30 90 upon the circular member in the well-known manner of band-brakes. The piston in cylinder 36 may be operated by the pressure-exerting fluid used in cylinders 12 and 16 or otherwise. To increase the resistance of the 95 brake-band 30 against rotary displacement, I prefer to construct it in two approximately equal sections and at a point approximately opposite fulcrum 33 secure the other ends of the sections to any convenient stationary 100 member, as indicated at 37, or in any desired manner.

To stop the car at the desired position and prevent longitudinal displacement, I mount "horns" 38 beside the rail, with a curved 115 portion extending over and above such rail adapted to engage the "tread" of the car-wheel. These horns I prefer to form integral with a plate pivotally secured in a horizontal position beneath the rail and so connected with springs 39 as to be held normally with the horns above the rail, as described, but adapted to be rotatorily displaced by an oncoming car to allow the car to be pushed off by the dumping device.

While I have described as a preferred form of operating the clamping members the use of cylinders and pistons, it is obvious that

- any other method of supplying sufficient pressure might be substituted—as, for instance, chains and winches or screw-pressure—and if such cylinders and pistons are used it is obvious that it is not necessary to use the particular form of four-way valve shown and described, as any convenient means for controlling the flow of the pressure-exerting medium would serve the same purpose.
5. In an application for Letters Patent for an improvement in car-dumping apparatus, Serial No. 203,755, filed by me on the 18th day of April, 1904, I have shown, described, and specifically claimed a rotary dumping device to turn a car entirely over and dump the contents, also means for retaining the car in position, as well as various other details shown and described in this application, and I do not, therefore, claim them herein.
- o. What I claim as novel, and desire to secure by Letters Patent, is—
1. In a device of the character described, a plurality of circular members rigidly mounted upon a common axis and a platform rigidly secured within such circular members, in combination with two railroad-tracks secured one on each side of and adjacent to the axis and having the individual rails of each track on opposite sides of but unequally distant from said axis.
  2. In a device of the character described, a plurality of circular members rigidly mounted upon a common axis, and a platform rigidly secured within and diametrical to the circular members in combination with two railroad-tracks secured one on each side of and adjacent to the axis and having the individual rails of each track on opposite sides of but unequally distant from said axis.
  3. In a device of the character described, a rotatable platform mounted upon an axis and adapted to support a car upon each face thereof, and means for clamping such cars in position to prevent displacement, in combination with two railroad-tracks one on each side of and adjacent to the axis and having the individual rails of each track on opposite sides of but unequally distant from said axis.
  4. In a device for unloading cars, a platform mounted upon an axis, a plurality of beams slidably mounted upon said platform and adapted to forcibly engage the top and sides of a car to prevent displacement of said car, in combination with two railroad-tracks secured one on each side of and adjacent to the axis and having the individual rails of each track on opposite sides of but unequally distant from said axis.
  5. In a device for unloading cars, a platform mounted upon an axis, a plurality of beams mounted upon said platform and adapted to forcibly bear upon the top of a car to prevent displacement of said car, in combination with two railroad-tracks secured one on each side of and adjacent to the axis and having the individual rails of each track on opposite sides of but unequally distant from said axis.
  6. In a device for unloading cars, an axis with a platform mounted thereon, a plurality of cylinders mounted upon said platform, pistons slidably disposed therein, means for admitting fluid within such cylinders to exert pressure upon the pistons and a plurality of beams connected with such pistons adapted to forcibly engage a car to prevent displacement thereof, in combination with two railroad-tracks secured one on each side of and adjacent to the axis and having the individual rails of each track on opposite sides of but unequally distant from said axis.
  7. In a device for unloading cars, an axis with a platform mounted thereon, a plurality of vertically-disposed cylinders mounted upon said platform, pistons slidably disposed therein, means for admitting fluid within such cylinders to exert pressure upon the pistons, a plurality of beams vertically slidably connected with such pistons and adapted to forcibly engage the top of a car to prevent displacement of said car, in combination with two railroad-tracks secured one on each side of and adjacent to the axis and having the individual rails of each track on opposite sides of but unequally distant from said axis.
  8. In a device for unloading cars, an axis with a platform mounted thereon, a plurality of horizontally-disposed cylinders mounted upon said platform, pistons slidably disposed therein, means for admitting fluid within such cylinders to exert pressure upon the pistons, a plurality of beams horizontally slidably and connected with such pistons, adapted to forcibly engage the sides of a car to prevent displacement of said car, in combination with two railroad-tracks secured one on each side of and adjacent to the axis and having the individual rails of each track on opposite sides of but unequally distant from said axis.
  9. In a device for unloading cars, an axis with a platform mounted thereon, a plurality of vertically-disposed cylinders mounted upon said platform, pistons slidably disposed therein, means for admitting fluid within such cylinders to exert pressure upon such pistons, a plurality of beams slidably connected with such pistons adapted to forcibly engage the top of a car, a plurality of horizontally-disposed cylinders mounted upon said platform, pistons slidably disposed therein, means for admitting fluid to such cylinders to exert pressure upon the pistons, a plurality of beams horizontally slidably connected with such pistons adapted to forcibly engage the sides of a car to prevent displacement of said car, in combination with two railroad-tracks secured one on each side of and adjacent to the axis and having the individual rails of each track on opposite sides of but unequally distant from said axis.

of and adjacent to the axis and having the individual rails of each track on opposite sides of but unequally distant from said axis.

10. In a device of the character described, 5 the combination of a plurality of circular members rigidly secured about an axis with a rotatable platform mounted thereon, a band extending entirely around one of such circular members and rigidly secured at its 10 middle point, its free ends engaging a pivotally-mounted cross-head, a lever rigidly secured to such cross-head and adapted to tighten such band about the circular member and two railroad-tracks secured one on each 15 side of and adjacent to the axis and having the individual rails of each track on opposite sides of but unequally distant from the axis.

11. In a device of the character described, 20 the combination of a plurality of circular members rigidly secured about an axis with a rotatable platform mounted thereon, a band extending entirely around one of such circular members and rigidly secured at its middle 25 point, its free end engaging a pivotally-mounted cross-head, a lever rigidly secured to such cross-head adapted to tighten such band about the circular member, a cylinder, a piston slidably disposed within such cylinder, a rod connecting the lever and the piston, 30 means for admitting fluid within the cylinder, adapted to exert pressure upon the piston and throw the lever, tightening the band and two railroad-tracks secured one on each side of and adjacent to the axis and having the individual 35 rails of each track on opposite sides of but unequally distant from the axis.

12. In a device for unloading cars, the combination of an axis with a platform mounted thereon, a plurality of cylinders mounted 40 upon said platform, pistons slidably disposed therein, pipes for admitting fluid within such cylinders to exert pressure upon the pistons, a plurality of beams connected with such pistons adapted to forcibly engage a car to prevent 45 displacement, means adapted to admit fluid to opposite ends of such cylinders to release such pressure and to return the pistons to their normal positions, means adapted to control the flow of fluid in the pipe system 50 and two railroad-tracks secured one on each side of and adjacent to the axis and having the individual rails of each track on opposite sides of but unequally distant from the axis.

13. In a device for unloading cars, the combination of an axis with a platform mounted 55 thereon, a plurality of vertically-disposed cylinders mounted upon said platform, pistons slidably disposed therein, means for admitting fluid within such cylinders to exert 60 pressure upon the pistons, a plurality of beams vertically slidably connected with such pistons and adapted to forcibly engage the top of a car to prevent displacement, and means adapted to admit fluid to the opposite

ends of such cylinders adapted to release 65 such pressure and return the pistons to their normal positions and two railroad-tracks secured one on each side of and adjacent to the axis and having the individual rails of each track on opposite sides of but unequally distant from the axis. 70

14. In a device for unloading cars, the combination of an axis with a platform mounted thereon, a plurality of horizontally-disposed cylinders mounted on said platform, pistons 75 slidably disposed therein, means for admitting fluid within such cylinders to exert pressure upon the pistons, a plurality of beams horizontally slidably and connected with such pistons, adapted to forcibly engage the 80 sides of a car to prevent displacement, means adapted to admit fluid to the opposite ends of such cylinders to release such pressure and return the pistons to their normal positions and two railroad-tracks secured one on each 85 side of and adjacent to the axis and having the individual rails of each track on opposite sides of but unequally distant from the axis.

15. In a device for unloading cars, the combination of an axis with a platform mounted 90 thereon, a plurality of vertically-disposed cylinders mounted on said platform, pistons slidably disposed therein, means for admitting fluid within such cylinders to exert pressure upon the pistons, a plurality of beams 95 slidably connected with such pistons adapted to forcibly engage the top of a car, a plurality of horizontally-disposed cylinders mounted upon said platform, pistons slidably disposed therein, means for admitting fluid to such cylinders to exert pressure upon the pistons, a plurality of beams horizontally slidably connected with such pistons, adapted to forcibly engage the sides of a car to prevent displacement, means adapted to admit fluid to the opposite ends of such cylinders to release such pressure and return the pistons to their normal positions and two railroad-tracks secured one on each side of and adjacent to the axis and having the individual rails of each track on opposite sides of but unequally distant from the axis. 100

16. In a device of the character described, the combination of a shaft rotatably journaled in two stationary abutments, a plurality of beams rigidly secured upon said shaft and arranged transversely thereto and parallel with each other, a plurality of guide-braces arranged in pairs on either side of, and perpendicular to said beams, a plurality of 11 members circularly embracing and rigidly secured to the structure, with said shaft disposed as a common axis and two railroad-tracks secured one on each side of and adjacent to the axis and having the individual rails of each track on opposite sides of but unequally distant from the axis. 12

17. In a device of the character described,

the combination of a shaft rotatably journaled in two stationary abutments, a plurality of beams rigidly secured upon said shaft and arranged transversely thereto and parallel with each other, a plurality of guide-braces arranged in pairs on either side of and perpendicular to said beams, a plurality of members circularly embracing and rigidly secured to the structure, with said shaft disposed as a common axis, one or more of said circular members being provided on its external periphery with gear-cogs, a pinion journaled eccentrically and externally to said circular member and adapted to engage said gear-cogs, means to rotate said pinion and circular member and two railroad-tracks secured one on each side of and adjacent to the axis and having the individual rails of each track on opposite sides of but unequally distant from the axis.

18. In a device of the character described, the combination of a shaft rotatably journaled in two stationary abutments, a plurality of beams rigidly secured upon and arranged transversely to said shaft and parallel with each other, a plurality of guide-braces arranged in pairs on either side of and perpendicular to the said beams, a plurality of members circularly embracing and rigidly secured to the structure, with said shaft disposed as a common axis, a plurality of cylinders arranged between and parallel with said guide-braces, pistons slidably disposed within the cylinders, rods connecting the pistons and beams adapted to clamp the sides of a car, pipes running from a point near the end of said shaft to all of said cylinders and adapted to admit fluid at the end opposite the piston-rod, pipes running from near the same point to all of said cylinders adapted to admit fluid to the opposite ends, a valve secured to the shaft near the end thereof and located in both pipe systems

adapted to control the flow of fluid and means for admitting fluid to such valve.

19. In a device of the character described, the combination of a shaft rotatably journaled in two stationary abutments, a plurality of beams rigidly secured upon said shaft and arranged transversely thereto and parallel with each other, a plurality of guide-braces arranged in pairs on either side of and perpendicular to said beams, a plurality of members circularly embracing and rigidly secured to the structure, with said shaft disposed as a common axis, a plurality of diagonally-disposed braces adapted to strengthen the structure, a plurality of cylinders arranged between and parallel with said guide-braces, pistons slidably disposed within the cylinders, rods connecting the pistons and beams adapted to clamp the top of a car, a plurality of cylinders arranged between and perpendicular to said guide-braces, pistons slidably disposed within the cylinders, rods connecting such pistons and beams adapted to clamp the sides of a car.

20. In a device of the character described, a rotatable dump secured upon an axial shaft journaled in two stationary abutments, an opening formed concentrically within one end of said shaft and extending throughout a portion of its length, a pipe for conducting fluid to said hollow end, a swivel-joint located adjacent and concentric to the hollow end of the shaft and connected therewith and with the said pipe and adapted to admit fluid to the hollow end of the shaft, valves secured to said shaft, openings adapted to admit fluid from said hollow shaft to the valves, a system of pipes connected with said valves, a plurality of cylinders adapted to receive fluid from said system of pipes and piston disposed within the cylinders connected with beams adapted to clamp a car.

ARTHUR MOORE.
